UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE.

OPEN-HEARTH PORT DESIGN

Application filed October 8, 1921. Serial No. 506,354.

This invention relates to a new and improved open hearth port design and more particularly to a design of this character adapted to provide a relatively restricted 5 incoming port area and relatively large area for the products of combustion upon the outgoing end.

Open hearth furnaces, as is well known in the art, are double-ended and reversible, being provided upon each end with ports, these ports serving upon the incoming end to introduce air and fuel and upon the outgoing end to conduct away the products of combustion. The products of combustion 10 considerably exceed in volume the incoming air and gas and, therefore, the port areas are largely designed with regard to the area necessary for carrying off the products of combustion. The port areas, in the 15 usual type of furnace, are, therefore, greater than is necessary or desirable upon the incoming end. These large port areas render it difficult to secure an adequate mixture of the air and fuel and also render it difficult 20 to properly control the flame. In general, the air is introduced upon either side and above the stream of gas or other fuel and the mixture of air and fuel takes place slowly as the elements pass across the furnace. This slow mixture gives a long flame 25 which does not adequately act upon the portion of the bath adjacent the incoming end and which further wears away the port walls upon the outgoing end.

It is highly desirable to secure a short, quick flame, and to secure such a flame, it is necessary that the air and fuel mix rapidly upon the meeting of the fuel and air streams. This mixture can be accomplished 30 by providing inwardly inclined portions of the furnace wall adapted to direct the incoming air at an angle toward the incoming gas stream. Such wall constructions, 35 however, reduce the effective area for passage of the combined air and fuel stream, and consequently, upon the outgoing end, reduce the area for the products of combustion. This reduced area requires that an 40 additional draft be provided in some man-

ner to adequately take care of the products of combustion.

Endeavors have been made to remedy this defect in regard to the outgoing end by provision of auxiliary passages for carrying 55 off the products of combustion, these passages being closed upon the incoming end by water-cooled dampers. While such a construction accomplishes the end sought, there are considerable heat losses due to the water-cooled apparatus, and the addition of this apparatus and of its operating mechanism somewhat complicates the furnace. 60

It is an object of the present invention to provide an open hearth port construction in which the incoming air is directed toward the incoming gas, and the combined stream passed through a restricted opening to secure a quick mixture and short flame, and in which auxiliary ports are 65 provided for carrying off the products of combustion from the outgoing end. 70

It is a further object to so design the auxiliary ports as to minimize any flow of air therethrough upon the incoming end. 75

It is an additional object to so design the junction of the auxiliary exhaust ports and the air passages as to minimize any tendency for air to flow from the passages to the ports. 80

It is also an object to provide means located at the junction of the auxiliary ports and the air passages adapted to aid in carrying the incoming air past the auxiliary port opening. 85

Other and further objects will appear as the description proceeds.

Broadly, my invention comprises the formation of a restricted passage in front of the air and fuel ports whereby the air is 90 directed into the fuel stream. It further provides additional exhaust passages leading from the melting chamber of the furnace to the air passages, preferably the air uptakes. The auxiliary passages are formed 95 smaller at their point of junction with the air passages in order to minimize any air coming from the air passages into the auxiliary ports, and preferably increase in size toward the melting chamber as shown in

Figure 1. These auxiliary ports preferably join with the air passages at a point below the air port level, and the brick work forming the lower portion of the auxiliary passage extends into the air passage to direct the air stream to pass the auxiliary port opening. Additional means for preventing incoming air from passing into the auxiliary ports are provided in the form of jets of compressed air forming an air curtain across the inner end of the auxiliary port. In the preferable form, these air jets carry with them a portion of the incoming pre-heated air which is by-passed from the main air passages.

I have illustrated certain preferred embodiments of my invention in the accompanying drawings in which—

Figure 1 is a longitudinal section of one end of an open hearth furnace constructed according to my design;

Figure 2 is a horizontal section of Figure 1 taken upon line 2—2; and

Figure 3 is a horizontal section of Figure 1 taken upon line 3—3.

Referring now to the drawings, the gas uptake 6 leads from the gas slag pocket 7 to the gas port 8, all of which are of usual construction. The air is led from air slag pocket 9 through the air uptakes 10, these uptakes joining above the gas port at 11. Air ports 12 are defined between gas port body 13 and the inwardly extending piers 14. These piers 14 together with the downwardly inclined portion 15 of the roof serve to direct the incoming air angularly toward the incoming air stream both from the sides and from above. The restricted area defined by the roof and the inner ends of the piers 14 serves to aid in causing a quick mixture of the air and gas. Auxiliary ports 16 are provided which lead from the outer face of the piers 14 downwardly to the air uptakes 10. These ports 16, as best shown in Figure 1, gradually decrease in cross-sectional area toward their point of junction with the air uptakes. The brick work 17 upon the lower face of the ports 16 extends into the air uptake 10 a greater distance than does the brick work upon the upper side of the ports 16. The air rising through the uptake is thus directed past the opening of the ports 16 into the uptake.

A slit 18 is provided extending transversely across the ports 16 substantially in line with the upper face of the port wall at its point of junction with the air uptake. This slit is provided with water-cooling means 19 to preserve its shape and area. Located below this slit is a pipe 20 provided with nozzles 21 and connected to any suitable source of compressed air. The slit 18 increases in area downwardly and its lower end 22 opens into the air uptake 10 adjacent the air slag pocket. The compressed air passing through

the nozzles 21 carries with it a thin sheet of air through the slit 18 and then this sheet of air acts as a curtain to close off the auxiliary passage 16.

In the operation of my furnace, upon the incoming end, the gas is passed through a slag pocket 7, uptake 6 and out through the port 8. The main body of incoming air passes through the slag pocket 9 and through the air uptakes 10 and joining at 11 forms a blanket of air enclosing the gas stream upon its sides and above. A relatively small amount of compressed air is introduced through the pipes 20 and nozzles 21 and serves to carry with it a small amount of the incoming pre-heated air through the bypass openings 22 and up through the slits 18. The brick work 17, the smaller area of the inner end of the port 16, and its location intermediate the length of the uptake also serve to minimize any flow of incoming air through the ports 16. The relative volume of compressed air is so small as to have but little cooling effect upon the whole volume of incoming air.

Upon the outgoing end, the products of combustion pass through the auxiliary ports 16 and also to some extent through the air ports 12 to the air uptakes 10 down which they pass to the air slag pocket 9 and to suitable regenerative chambers which have not been shown as they are well known in the art. A portion also of the exhaust gases passes through the gas port 8 and down through the gas uptake 6 to the gas slag pocket 7 and thence through the gas regenerators.

I have shown a number of methods combined to minimize the flow of the incoming air through the auxiliary ports and any or all of them may be used. My invention is susceptible of many modifications and changes to meet varying conditions and it is my intention to cover all such changes as come within the spirit and scope of the appended claims.

I claim:

1. In an open hearth furnace, air and gas uptakes leading to air and gas ports at each end of the furnace, discharge passages for the products of combustion connecting the melting chamber and air uptakes, and means adapted to prevent flow of air through said discharge passages upon the incoming end of the furnace.

2. In an open hearth furnace, air and fuel ports and passages in the furnace ends, inwardly inclined piers in the furnace defining a relatively restricted passage between the ports and melting chamber and auxiliary discharge ports extending through said piers, and leading to the air passages.

3. In an open hearth furnace, air and fuel ports in the furnace ends, inwardly inclined piers in the furnace defining a relatively re-

stricted passage between the ports and melting chamber and auxiliary discharge ports extending through said piers, and means adapted to prevent passage of air through 5 said auxiliary passages on the incoming end of the furnace.

4. In an open hearth furnace, air and fuel ports and uptakes in the furnace ends, piers in the furnace defining a relatively restricted 10 passage between the ports and melting chamber and auxiliary discharge ports extending through said piers, and leading to the air uptakes below the air ports.

5. In an open hearth furnace, air and fuel 15 ports and passages in the furnace ends, piers in the furnace defining a relatively restricted passage between the ports and melting chamber and auxiliary discharge ports extending through said piers, and leading to 20 the air passages, said passages decreasing in size from the melting chamber.

6. In an open hearth furnace, air and gas 25 uptakes leading to air and gas ports at each end of the furnace, and discharge passages for the products of combustion connecting the melting chamber and air uptakes, said passages decreasing in size from the melting chamber.

7. In an open hearth furnace, air and fuel 30 ports and passages in the furnace ends, and auxiliary discharge ports connecting the melting chamber and air passages, said ports decreasing in size from the melting chamber toward their junction with the air 35 passages.

8. In an open hearth furnace, air and fuel ports and passages in the furnace ends, and auxiliary discharge ports connecting the melting chamber and air passages, the lower 40 wall of the auxiliary ports extending into the air passages whereby air coming in through the passages is deflected past the opening of the auxiliary port.

9. In an open hearth furnace, air and fuel 45 ports and passages in the furnace ends, and auxiliary discharge ports connecting the melting chamber and air passages, and means adapted to produce a curtain of air across the opening of said auxiliary ports 50 from the air passages to prevent flow of air through said auxiliary ports on the incoming end of the furnace.

10. In an open hearth furnace, air and fuel ports and passages in the furnace ends, and auxiliary discharge ports connecting the melting chamber and air passages, and means adapted to by-pass a portion of the incoming air across the opening of said auxiliary ports from the air passages, said air 60 forming a curtain to prevent flow of air through said ports on the incoming end of the furnace.

11. In an open hearth furnace, air and fuel ports and passages in the furnace ends, and auxiliary discharge ports connecting 65

the melting chamber and air passages, and means including a by-pass passage terminating in a slit across the lower face of the auxiliary port, adapted to by-pass a portion of the incoming air across the opening of 70 said auxiliary ports from the air passages, said air forming a curtain to prevent flow of air through said ports on the incoming end of the furnace.

12. In an open hearth furnace, air and fuel ports and passages in the furnace ends, and auxiliary discharge ports connecting the melting chamber and air passages, and means including a by-pass passage terminating 75 in a slit across the lower face of the auxiliary port, and compressed air nozzles adapted to induce flow of air through said by-pass and slit adapted to by-pass a portion of the incoming air across the opening of said auxiliary ports from the air passages, 80 said air forming a curtain to prevent flow of air through said ports on the incoming end of the furnace.

13. In an open hearth furnace having small port area for the incoming air and 90 gas and additional port area for the outgoing products of combustion, and connecting passages associated with said ports, compressed fluid means operating in said passages whereby the flow of incoming air is 95 controlled and directed to said small port area.

14. In an open hearth furnace, air and fuel ports and passages, a passage opening 100 from the air passage, and means adapted to discharge compressed fluid whereby a flow of air through said passage from the air passage is induced.

15. In an open hearth furnace, air and fuel ports and uptakes, a passage opening 105 from the air uptake, and means adapted to discharge compressed fluid whereby a flow of air through said passage from the air uptake is induced.

16. In an open hearth furnace, air and fuel ports, air uptakes, passages leading from said uptakes and nozzles adapted to discharge compressed fluid in the passages whereby a flow of air from the uptake through the passages is induced. 110

17. A metallurgical furnace comprising a hearth, a combined fuel and air port at each end of the furnace having a constricted discharge orifice, flues at each end of the furnace on opposite sides of the combined fuel and air ports and communicating with the furnace and with the combined fuel and air ports, and means for feeding fuel and air into the furnace through the combined fuel and air ports. 120
